[57] CLAIM

The ornamental design for a portion of a console trim strip,
as shown and described.

DESCRIPTION

FIG. 1 is a perspective view of a portion of a console trim strip showing our new design, the broken lines are shown for
illustrative purposes only and form no part of the claimed
design; and,

FIG. 2 is a top plan view thereof.

The front, rear, bottom and side views of the design are not
visible in their normal intended use.
